UNITED STATES PATENT OFFICE.

HARRISON H. SOUTHWORTH, OF CLEVELAND, OHIO, ASSIGNOR, BY MESNE ASSIGNMENTS, TO THE ICELESS MACHINE COMPANY, OF CLEVELAND, OHIO, A CORPORATION OF OHIO.

REFRIGERATING APPARATUS.

1,162,313.

Specification of Letters Patent. Patented Nov. 30, 1915.

Application filed November 22, 1912. Serial No. 732,807.

To all whom it may concern:

Be it known that I, HARRISON H. SOUTHWORTH, a citizen of the United States, and a resident of Cleveland, in the county of Cuyahoga and State of Ohio, have invented certain new and useful Improvements in Refrigerating Apparatus; and I do hereby declare that the following is a full, clear, and exact description thereof, reference being had to the accompanying drawings, and to the letters of reference marked thereon, which form a part of this specification.

This invention relates to an improvement in refrigerating apparatus and particularly to the means for controlling the cooling and heating media in an absorption refrigeration apparatus in which a single generator-absorber is used which acts alternately as a generator and as an absorber.

In my improved refrigerating apparatus practically all of the ammonia in the system, (except the small amount left in the weak liquor in the generator-absorber) is driven from the generator-absorber to the condenser during the period of generation and practically all of said ammonia passes from the condenser through the refrigerating coils to the generator-absorber during the period of absorption, there being no surplus ammonia in the system to continue the process of refrigeration at the time when the generator-absorber has reached the end of its period of absorption and begins its period of generation.

The invention consists of the matters hereinafter described and more particularly pointed out in the appended claims.

In the drawings:—Figure 1 is a view representing in side elevation an apparatus embodying my invention. Fig. 2 is a view representing a front elevation of the same. Fig. 3 is a view representing, on an enlarged scale, a partial vertical section through Fig. 1, as indicated by the line 3—3 of Fig. 1. Fig. 4 is a view representing a vertical section through one of the diaphragm casings that will be referred to more particularly later. Fig. 5 is a partial vertical section on an enlarged scale in a plane indicated by the line 5—5 of Fig. 3. Fig. 6 is a partial horizontal section on a like scale in a plane indicated by the line 6—6 of Fig. 3. Fig. 7 is a perspec-

tive view of one of the operating arms used to control the movement of the burner. Fig. 8 is a vertical central section of a valve mechanism interposed in the conduit leading to the refrigerating coils.

Referring now to that embodiment of my invention illustrated in the drawings, 10 indicates a drum or still which may be of any suitable construction adapting it to act as a generator-absorber in a refrigerating apparatus using a distillant refrigerant preferably ammonia.

11 indicates a drum which may be of like construction and which is adapted to act as an ammonia condenser and liquid ammonia receiver. It will be hereinafter called a condenser. Said drums are supported upon a suitable frame 12 which stands in an oblong tank 12^a adapted to contain cooling water.

The generator-absorber drum 10 is connected to the condenser drum 11 by a pipe 13 through which the ammonia gas driven from the liquor in the drum 10 during the process of generation, is led into the drum 11 wherein it is condensed, a check valve 13^x on this pipe preventing back flow.

14 indicates a return-pipe leading from the refrigerating coil back to the generator-absorber drum 10 and adapted to direct the expanded ammonia gas after it has done its work in the refrigerating coil back into said generator-absorber.

14^x indicates a check-valve to prevent a back flow from the generator-absorber to the refrigerating coils during the process of generation.

15 indicates a burner comprising a rock-shaft pipe 16 which is connected with the source of gas supply in a familiar manner and a longitudinally extending pipe 17 provided with suitable openings and constituting a burner-pipe through which the gas is adapted to escape when the burner is acting to heat the generator-absorber. Fixed to and swinging with said burner are two troughs 18, 19, located at either side of the burner and extending parallel thereto.

Above the generator-absorber drum is located a cooling water tank 20 which extends longitudinally of said drum and through which a part 13^a of the pipe 13, connecting

the generator-absorber with the condenser, passes in order to cool and rectify the ammonia gas driven off from the generator. Below said tank is placed a longitudinally extending pipe 21 which is placed immediately above the generator-absorber 10 and is provided with openings to discharge cooling water upon the same. Said pipe is connected to a funnel 21^a arranged adjacent the rear end of and attached to the side of the cooling water tank 20. An overflow pipe 20^a, connected to the opposite side of the tank 20, leads down to a point below the generator-absorber where it has a discharge nozzle 15 20^b adapted to discharge water into one of the tanks fixed to the burner, namely, the tank 19, when the same is brought into position below it.

22 indicates a water supply pipe provided with a spout 22^a capable of oscillatory movement and arranged to discharge water into the funnel 21^a or into the tank 200. Said spout is oscillated by a lever 23 (see Fig. 1) which, as shown, is fulcrumed on a pin 23^a fixed to the rear end of the drum 10 and has a fork 23^b at its lower end that engages a rearward projecting rod or pipe 17^a on the burner pipe. Thus when the burner swings, the lever 23 will swing with it. A 30 forwardly projecting forked arm 23^c is provided at the upper end of the lever 23 for engagement with the water spout 22^a. Thus the movement of the burner will cause the spout 22^a to swing from a position above the funnel 21^a to a position above the tank 20 and back again in a manner presently to be described.

24 indicates a radial rock-arm made rigid with the rock-shaft pipe 16 and carrying at 40 its end a quadrant 24^a provided with oppositely facing, spaced radial shoulders 25, 26.

27 indicates a casing containing a chamber 27^a (see Fig. 4) in which is located a diaphragm 27^b. Said casing is connected 45 on its lower side by a pipe 27^c with the condenser 11 so that the diaphragm 27^b is subjected to the pressure in the condenser. The diaphragm 27^b is arranged to actuate a vertically movable stem 28 located above it and 50 projecting through the upper part of the casing in a position to engage a horizontally disposed lever 29 which is fulcrumed on the casing 27.

30 indicates the fulcrum of said lever placed intermediate the stem 28 and the burner 15.

The outer end of the lever 29 is connected by a coiled spring 31 with a fixed part of the casing 27. To the inner end of the lever 29 60 is connected a depending link 32 which has operative connection at its lower end with an arm 33, (see Figs. 2 and 3) that is fulcrumed to swing in a vertical plane on an upright lug 34 made rigid with a transverse bar 35^c on the main supporting frame 12.

The inner end of the arm 33 is preferably constructed so as to yield in an upward direction with reference to the main part of the arm while being made incapable of yielding movement in a downward direction 70 with reference thereto and to this end said lever 33 as shown has an extension 35 pivotally connected to it. Said extension 35 is provided at its inner end with a lug 33^b arranged to engage one of the shoulders on 75 the quadrant 24^a (as shown the radial shoulder 25). The extension 35 and the lever 33 have, on their lower sides, abutting shoulders or lugs 33^a, 35^a, respectively, and a spring 36 fixed to the lever 33 and engaged 80 with the upper edge of the extension 35, yieldingly engages the said extension so as to normally hold the extension in such position, with reference to the arm 33, that the two shoulders 33^a and 35^a are normally in 85 engagement. The purpose of this construction will appear presently.

37 indicates a second diaphragm casing which may be of a construction similar to that of the casing 27. The top side of said 90 casing is connected to a pipe 38 containing a fluid adapted to boil at a comparatively low temperature to be predetermined and which pipe extends into the generator-absorber drum 10, so as to be affected by the 95 temperature maintained in said drum. The pressure in the said fluid pipe acts on a diaphragm within the casing as before which is arranged to engage a vertically movable stem 39.

40 indicates a lever fulcrumed at 41 to the lower side of the casing 37 and having one arm 40^a which is engaged by the stem 39. The other arm 40^b of said lever 40 carries a depending link 42 (see Fig. 3) which is operatively connected with a vertically swinging arm 43 pivoted on an upright lug 44 rising from the transverse bar 35^c of the main frame. The arm 43 has a pivoted extension 45 carrying a laterally extending lug 110 45^b adapted for engagement with one of the radial shoulders of the quadrant 24^a, in this case, the shoulder 26. Said extension, as in the case of the arm 33 is made so as to yield in an upward direction with reference 115 to the arm 43 whereas it is fixed against downward movement with reference to said arm, 43^a, 45^a representing the engaging lugs on said extension and arm and 46 the spring to yieldingly resist the upward relative 120 movement of the extension with reference to the said arm.

The arm 40^b of the lever 40 is connected, as shown herein, by means of a coiled spring 48 with the transverse bar 35^c of the main 125 frame, which spring determines the pressure required to be induced in the steam pipe 38 and in the casing 37 in order to cause sufficient pressure to actuate the lever 40 so as to raise the arm 43. As shown, the ends of the 130

spring 48 are provided with adjusting nuts to adjust the tension.

5 Fuel gas is supplied to the burner through the rock-shaft pipe 16 by means of a main supply pipe 50 containing a spring controlled valve mechanism 51 of familiar construction (see Fig. 5). The valve is opened by means of a stem 52 which projects outwardly through the valve casing and is 10 adapted for engagement with one arm of a bell-crank lever 53 fulcrumed on a fixed arm 54 that is made integral, as shown, with the valve casing. The other arm of the bell-crank lever is connected by a link 54^a with 15 a radially projecting pin 55 on the burner rock-shaft pipe 16.

When the burner is in heating position under the drum 10, as shown in Fig. 2, the bell-crank lever 53 acts, by its engagement 20 with the valve stem 52 to hold the valve open so as to permit a free supply of fuel gas to the burner. When the burner swings to the right from the position shown in Fig. 1 to the position shown in Fig. 2, the rock- 25 ing movement of the rock-shaft pipe 16 swings the bell-crank lever 53 downward and relieves the valve stem of the pressure of said lever, whereupon the valve is closed.

I prefer to provide, as shown, a pilot 30 burner 56 located near one end of the drum and connected to the main gas supply pipe 50 at a point above the valve 51. Said pilot burner is placed in the neighborhood of the burning position of the burner, so that when 35 the gas is turned on in the burner it will be lighted by the pilot flame. I also provide a transversely curved plate 12^x spaced a short distance from the drum 10 and extending longitudinally thereof. Said plate 40 constitutes a shield and acts to prevent water from dripping from the sides of the drum 10 upon the burner when the burner is in the position shown in Fig. 3 and the said drum is acting as an absorber. It also has 45 another function to be mentioned later.

57^x indicates a pipe or conduit for conveying the liquid ammonia to the refrigerating coil. A valve 57 (see Figs. 2 and 8) is 50 interposed in the pipe 57^x. Said valve is controlled by a diaphragm which is subjected to the pressure of the generator-absorber.

58 indicates a diaphragm casing connected 55 with the casing of the valve 57 and containing a diaphragm 59. The upper side of the casing 58 is connected by a pipe 60 with the return-pipe 14 so that the diaphragm is always subjected to the pressure of the generator-absorber. The diaphragm is adapted 60 to actuate a spring-controlled rod or stem 61 to bring it into engagement with the movable part of the valve 57, in this case a ball 62, and lock it on its seat.

65 The construction is such that liquid ammonia may freely pass through the valve 57

on its way to the refrigerating coils, except when the pressure of the generator-absorber and the return-pipe 14 has risen to a predetermined point where it is sufficient to depress the spring-controlled stem 61, in 70 which case the valve will be locked on its seat and the further passage of refrigerant through the pipe 57^x will be prevented until the pressure in the generator-absorber falls below the aforesaid predetermined pressure. 75 This occurs at the time the drum 10 ceases to act as an absorber and begins to act as a generator so that a flow of refrigerant from the condenser to the refrigerating coils during the process of generation is made im- 80 possible.

The operation of my improved apparatus is as follows: With the parts of the apparatus in the position shown in Fig. 2, the burner is directly under the generator-absorber and the gas supply controlling valve 51 is open, so that the generator-absorber is being heated and ammonia gas is being driven from the generator-absorber through the pipe 13 to the condenser 11. 90 As the generator-absorber is being heated, a high pressure exists in the return pipe 14 so that the ball-valve 62 is locked upon its seat and no refrigerant can pass to the refrigerating coils and the process of refrigeration is in abeyance. The water discharge nozzle 22^a is directing cooling water into the tank 20 containing the rectifying coil 13^a of the ammonia discharge pipe 13 and water is overflowing from said tank 100 through the pipe 20^a into the tank 19. This condition of affairs continues until a predetermined temperature is reached in the generator-absorber drum 10 corresponding with and indicating the degree of weakness of 105 the liquor in the drum that the apparatus is designed to work to. This temperature, communicated to the steam pipe 38 will cause sufficient pressure therein and in the diaphragm casing 37 to cause the dia- 110 phragm to depress the stem 39 and operate the lever 40 against the downward pull of its controlling spring 48 so as to cause it to raise the arm 43 and remove its laterally ex- 115 tending lug 45^b above its engaging position with the radial shoulder 26 of the quadrant 24^a. This releases the burner, which, by reason of the weight of water in the trough 19, is caused to swing to the right to the position indicated in Fig. 3, when the other shoulder 25 of the quadrant is engaged by the lug 33^b of the arm 33. This movement of the burner as has been described, swings the bell-crank lever 53 from its operative 120 engagement with the fuel gas supply valve 125 stem 52 so as to permit said valve to close and cut off the supply of gas to the burner. This movement of the burner also through the extension rod 17^a and the lever 23 shifts the water discharge nozzle 22^a from its 130

position above the tank 20 to a position above the funnel 21^a. This stops a further flow of water through the overflow pipe 20^a and directs the cooling water into the cooling water pipe 21 above the generator-absorber so as to discharge cooling water on the same. This starts the process of absorption in the drum 10 and as the pressure in the return-pipe 14 is after the drum is cooled 10 lowered beyond the predetermined point at which it is designed to depress the diaphragm 59 controlling the valve 62, said valve is released and the liquid ammonia in the condenser is free to flow toward the refrigerating coil and the process of refrigeration begins. The water which flows from the pipe 21 flows down about the sides of the drum 10 and falls into the trough 18 which now is in a position to receive the 15 water dropping from said drum. The shield 12^x directs the water into the trough 18 from that side of the drum farthest from the said trough. In the meantime the water in the other trough is flowing through and discharging from said trough into the tank 12^a through openings 19^a in said trough which are large enough to permit said trough to become emptied before the next movement of the burner is required, but which are 20 small enough to permit the trough to fill when water is being directed into it from the overflow pipe 28 notwithstanding the presence of said opening 19^a. (The trough 18 is provided with similar openings 18^a for 25 a similar purpose). The parts remain in this position until all of the liquid ammonia in the condenser has passed therefrom whereupon the pressure in said condenser will drop. This produces a drop of the pressure 30 in the diaphragm casing 27 so that the diaphragm therein will no longer hold the stem 28 against the downward action of the spring 31 on the lever 29 whereupon said lever will be swung to raise the arm 33 and thus relieve the lug 33^b at the free end 35 of said arm from its engagement with the shoulder 25. The weight of water in the trough 18 thereupon swings the burner into its first position which movement causes the nozzle 22^a to swing into position above the tank 20 and causes the bell-crank lever 53 to act upon the fuel gas supply valve stem 52 and open said valve, whereupon the burner will be again lighted by the pilot 40 light and the period of generation in the generator-absorber will be again started. This raises the pressure in the generator-absorber and in the return-pipe 14 on the side of the check-valve 14^x next the same, beyond 45 the predetermined degree, the ball-valve 62 will be again locked on its seat and the period of refrigeration again stopped. The yielding extensions 35 of the arms 33 are provided so that the downward pressure of 50 the said arms on the quadrant intermediate

the period when the lugs carried by said arms are in engagement with their respective radial shoulders on the quadrant may not cause friction to resist the movement of the quadrant when the burner moves from one position to another as above described. 70

Suitable shoulders 35^y (see Fig. 6) are provided on the transverse bar 35^c to act as stops for engagement with a pin 35^x on the burner to limit its movement in either direction. 75

In a refrigerating apparatus of the kind described herein wherein the process of refrigeration is in abeyance during one cycle of operation of the apparatus, that is to say, 80 during the period of generation of the refrigerant, it is preferable to place the refrigerating coils in a tank of brine so that the rise of temperature will be comparatively slight during the intermission of the action 85 of the refrigerating coils. 90

I claim as my invention:—

1. In a refrigerating apparatus of the absorption type, in combination with a generator-absorber, a condenser, and means for cooling and means for heating said generator-absorber in alternation, means acting to discontinue the heating of said generator-absorber when the absorbent therein has been reduced to a predetermined degree of 95 weakness and means for discontinuing the cooling of said generator-absorber when the liquid refrigerant in the condenser has been exhausted. 100

2. In a refrigerating apparatus of the absorption type, in combination with a generator-absorber, a condenser, and means for cooling and means for heating said generator-absorber in alternation, means acting to discontinue the heating of said generator-absorber when it has been heated to a predetermined degree of temperature, and means for discontinuing the cooling of said generator-absorber when the pressure in the condenser has fallen below a predetermined 110 point. 105

3. In a refrigerating apparatus of the absorption type, in combination with a generator-absorber, a condenser, and means for cooling and means for heating said generator-absorber in alternation, means acting to discontinue the heating of said generator-absorber and for starting the cooling thereof when the absorbent therein has been reduced to a predetermined degree of weakness, and means for discontinuing the cooling of the generator-absorber and for starting the heating thereof when the liquid refrigerant in the condenser has been exhausted. 115 120

4. In a refrigerating apparatus of the absorption type, in combination with a generator-absorber and a condenser, and means for cooling and means for heating the generator-absorber in alternation, means acting 125 130

- to discontinue the heating of said generator-absorber and for beginning the cooling thereof when the absorbent therein has been raised to a predetermined degree of temperature, and means for discontinuing the cooling of said generator-absorber and for starting the heating thereof when the pressure in said condenser has fallen below a predetermined point. 5 70
- 10 5. In a refrigerating apparatus of the absorption type, in combination with a generator-absorber, a condenser, and means for cooling and means for heating said generator-absorber in alternation, means acting to discontinue the heating of said generator-absorber when the absorbent therein has been reduced to a predetermined degree of weakness, means for discontinuing the cooling of said generator-absorber when the liquid refrigerant in the condenser has been exhausted, and means for automatically shutting off the flow of refrigerant from the condenser during the period while the generator-absorber is generating. 15 80
- 20 6. In a refrigerating apparatus of the absorption type, in combination with a generator-absorber, a condenser, and means for cooling and means for heating said generator-absorber in alternation, means acting to discontinue the heating of said generator-absorber when it has been heated to a predetermined degree of temperature, means for discontinuing the cooling of said generator-absorber when the pressure in the condenser has fallen below a predetermined point, and means for shutting off the flow from the condenser when a predetermined pressure has been reached in the generator-absorber. 30 90
- 35 7. In a refrigerating apparatus of the absorption type, in combination with a generator-absorber, a condenser, means for cooling and means for heating said generator-absorber in alternation, means acting to discontinue the heating of said generator-absorber when the absorbent therein has been reduced to a predetermined degree of weakness and for simultaneously starting the cooling thereof, means for discontinuing the cooling of the generator-absorber when the liquid refrigerant in the condenser has been exhausted and for simultaneously starting the heating of said generator-absorber, and means for automatically shutting off the flow from the condenser at the time the generator-absorber begins to be heated. 45 100
- 50 8. In a refrigerating apparatus of the absorption type, in combination with a generator-absorber and a condenser, means for cooling and means for heating the generator-absorber in alternation, means acting to discontinue the heating of said generator-absorber and for beginning the cooling thereof when the absorbent in said generator-absorber has been raised to a predetermined degree of temperature, and for discontinuing the cooling of said generator-absorber and for starting the heating thereof when the pressure in said condenser has fallen below a predetermined point, and means for automatically shutting off the flow from the condenser while the pressure in the generator-absorber exceeds a certain amount. 55 110
- 60 9. In a refrigerating apparatus of the absorption type, in combination with a generator-absorber, a condenser, and means for cooling and means for heating said generator-absorber in alternation, the cooling and heating periods of said generator-absorber constituting successive cycles of its operation, means for reversing said cycles, depending for its operation upon a predetermined low degree of saturation in the generator-absorber and upon a predetermined degree of exhaustion of liquid refrigerant in the condenser, and means for shutting off the flow from the condenser during the heating cycle of the generator-absorber. 65 120
- 65 10. In a refrigerating apparatus of the absorption type, in combination with a generator-absorber, a return conduit for leading the expanded refrigerant back to the generator-absorber, a condenser, a discharge conduit connecting the generator-absorber with the condenser, a third conduit leading from the condenser to the refrigerating coils, and means for cooling and means for heating said generator-absorber in alternation, a thermostatic device connected with the generator-absorber acting to discontinue the heating of said generator-absorber and to start the cooling thereof when the absorbent therein has been raised to a predetermined degree of temperature, pressure actuated means connected with the condenser for discontinuing the cooling of said generator-absorber and for starting the heating thereof when the pressure in the condenser has fallen below a predetermined point, a valve in said third conduit, and pressure actuated means connected with said generator-absorber for positively closing said valve while the pressure in said generator-absorber exceeds a predetermined amount. 70 130
- 70 11. In a refrigerating apparatus, the combination, with generating and absorbing means, a stationary liquid refrigerant container, means for heating the liquor, means for cooling the liquor, means for automatically terminating the heating and starting the cooling, and means for automatically terminating the cooling and starting the heating consequent upon the exhaustion of liquid refrigerant from the container. 75 140
- 75 12. In an absorption refrigeration apparatus, the combination of a still, a container for liquid refrigerant, a connection between the still and the container, and a connection between the container and the absorption apparatus. 80 150

- the same and the still, means for heating the still, means for cooling the still, means for terminating the heating under the control of the temperature within the still, 5 means for terminating the cooling by the exhaustion of the liquid refrigerant from its container.
13. In an absorption refrigeration apparatus, the combination, with a still and a stationary liquid refrigerant container, of means for heating the still, means for cooling the still, means for automatically turning off the heat to terminate a generation period, and a device responsive to the fluid pressure within the container for automatically terminating an absorption period consequent upon the complete exhaustion of liquid refrigerant from the container.
14. In an absorption refrigeration apparatus, the combination of a closed vessel adapted to contain volatile liquor, a high pressure conduit leading from the vessel, a low pressure conduit leading to the vessel, means for cooling the liquor in the vessel, 25 means responsive to fluid pressure for terminating the cooling operation dependent on the complete exhaustion of liquid refrigerant on the high pressure side of the apparatus.
15. In an absorption refrigeration apparatus, the combination with a generator-absorber provided with heating and cooling means and acting alternately as a generator and as an absorber, a liquid refrigerant container into which the generator-absorber is adapted to discharge, means for automatically turning off the heat and turning on the cooling medium to terminate a generating period and start an absorption period, 35 means responsive to fluid pressure for terminating the absorption operation and re-establishing the generating operation dependent on the complete exhaustion of liquid refrigerant from the container.
16. In an absorption refrigeration apparatus, the combination with an expansion coil, of generating and absorbing means, a condenser, a check valve between the generating means and the condenser, means automatically terminating the generation period consequent upon the temperature on the generating side of the check valve, and means automatically terminating the absorption period consequent on the fluid pressure between the check valve and expansion coil.
17. In an absorption refrigeration apparatus of the intermittent type, the combination of a still, means for heating it, means 60 for cooling it, a container for liquid refrigerant, a connection between the container and the still, a thermostat in the still, a pressure device connected with the container, and means whereby the thermostat controls the duration of the heating opera-

tion and the pressure device controls the duration of the cooling operation.

18. In a refrigerating apparatus, the combination, with a generator-absorber, of a stationary container for a liquid refrigerant, and means for controlling a reversal of function of the generator-absorber by the complete exhaustion of liquid refrigerant on the high pressure side of the apparatus. 70

19. In an absorption refrigeration apparatus of the intermittent type, the combination, with a generator-absorber, of means responsive to fluid pressure for controlling the termination of the absorption period dependent upon the complete exhaustion of liquid refrigerant on the high pressure side of the apparatus. 75

20. In a refrigerating apparatus, the combination of a generator-absorber, a receptacle for ammonia condensed to a liquid, 80 means for causing the generator-absorber to be a generator, means for causing the generator-absorber to be an absorber, and means for terminating the absorption period consequent upon the exhaustion of liquid anhydrous ammonia from the receptacle. 85

21. In a refrigerating apparatus of the absorption type, the combination of a generator-absorber, a condenser, means for causing the generator-absorber to act alternately as a generator and as an absorber, and means for preventing the flow of refrigerant from the condenser when a predetermined pressure has been reached in the generator-absorber. 90

22. In a refrigerating apparatus of the absorption type, the combination of a generator-absorber acting alternately as a generator and as an absorber, a condenser, a passage leading therefrom, and means for shutting off the flow through said passage when the pressure in the generator-absorber has reached a predetermined point. 105

23. In a refrigerating apparatus of the absorption type, the combination of a generator-absorber, a condenser, a conduit from the condenser to the generator-absorber, and means for shutting off the flow from the condenser through said conduit, including a pressure-responsive device dependent for its operation on the pressure within the generator-absorber. 110

24. In a refrigerating apparatus of the absorption type, the combination of a generator-absorber, a condenser connected therewith, conduits between the generator-absorber and the condenser and from the condenser leading back to the generator-absorber, a valve for closing the last mentioned conduit including a pressure responsive device adapted to be closed by a predetermined pressure in the generator-absorber and opened by a reduction in said pressure to a predetermined amount, means for heating the generator-absorber, means for cooling it, 115

120

125

130

and means for automatically turning off the heat and turning on the cooling medium to terminate the generation period, said termination being followed automatically by an 5 absorption period, and means for terminating the absorption period consequent upon the exhaustion of liquid refrigerant from the container.

25. In a refrigeration apparatus of the absorption type, the combination with generating and absorbing means, of a liquid refrigerant container, a thermostat responsive to the temperature in the generator, means under the control of the thermostat for automatically turning off the heat and turning on cooling medium, and means for terminating an absorption period consequent upon exhaustion of liquid refrigerant from the container.

26. In a refrigeration apparatus of the absorption type, the combination with generating and absorbing means, of a stationary liquid refrigerant container, and means for terminating an absorption period consequent upon 25 the exhaustion of liquid refrigerant from the container.

27. In a refrigerating apparatus of the absorption type, the combination of a liquid refrigerant container, an absorber, an expansion coil, and conduits leading from the container to the expansion coil and from the expansion coil to the absorber, a fluid pressure device connected with the liquid refrigerant container, and means actuated by 35 said device for terminating an absorption period.

28. In a refrigerating apparatus of the absorption type, the combination with generating and absorbing means, of a liquid refrigerant container, a fluid pressure device in communication therewith, means actuated by said fluid pressure device for terminating an absorption period consequent upon an exhaustion of liquid refrigerant from the container, and means for terminating a generating period consequent upon a predetermined weakness of the liquor in the generator.

29. In a refrigerating apparatus of the absorption type, the combination with heating and cooling means, of a liquid refrigerant container, devices for stopping the heating operation, and a fluid pressure device in connection with the container adapted to 55 stop the absorbing operation.

30. In a refrigerating apparatus, the combination, with an absorber, of a container for liquid refrigerant, and means responsive to fluid pressure for terminating the absorption period consequent upon complete exhaustion of liquid refrigerant from the container.

31. In a refrigerating apparatus, the combination with generating and absorbing means, of a liquid refrigerant container, a

fluid pressure device connected with the container and having a diaphragm, and mechanism operated by said device for controlling the heating means.

32. In a refrigerating apparatus, the combination with generating means having a shiftable burner, of a liquid refrigerant container, a pressure responsive device actuated consequent upon the exhaustion of liquid refrigerant from the container, and 75 mechanism operated by the pressure responsive device for shifting the burner.

33. The combination, with generating and absorbing means, of a burner member, a shield member, one of said members being 80 shiftable with relation to the other, means for supplying water, a device for turning on the water, and shifting the relative positions of the burner and shield to cause the shield to protect the burner, a liquid refrigerant container, and pressure mechanism connected therewith for controlling said device.

34. The combination with generating and absorbing means, of a shiftable burner, 90 means for supplying water, a shield, a device for simultaneously shifting the burner to a position under the shield and turning on the water, a liquid refrigerant container, and pressure mechanism connected there- 95 with for controlling said device.

35. In a refrigerating apparatus, the combination with a generator, a burner therefor, a liquid refrigerant container, a chamber connected with the liquid refrigerant container, a movable diaphragm therein, a lever operated by the diaphragm, a tripping device controlled by said lever, and means whereby the tripping device may turn on the burner.

36. In an absorption refrigeration apparatus, the combination with absorbing means and a receptacle for liquid refrigerant, of a device adapted to have a movement resulting from the dropping of pressure in 110 the receptacle consequent upon the exhaustion of liquid refrigerant therein, and power operated means for terminating the absorption period controlled by said device.

37. In an apparatus of the character described, the combination, with generating and absorbing means, of a condenser, means for supplying cooling medium thereto, means for controlling the application of such supply to the refrigerating medium including a device having a movement dependent upon pressure conditions in the condenser, and a power device controlled by the device first mentioned and operating to terminate the absorption period.

38. In an absorption refrigeration apparatus, the combination with a stationary receptacle for liquid refrigerant and an absorber, of means for supplying a cooling medium to the absorber, power means for 130

terminating the absorption period, and a controlling device for said power means dependent on the exhaustion of liquid refrigerant from its receptacle.

- 5 In testimony that I claim the foregoing as my invention I affix my signature, in the

presence of two witnesses, this 18th day of November, A. D. 1912.

HARRISON H. SOUTHWORTH.
